H. H. SCHROYER.
CAR VESTIBULE DIAPHRAGM.
APPLICATION FILED APR. 8, 1912.

1,125,740.

Patented Jan. 19, 1915.

UNITED STATES PATENT OFFICE.

HARRY H. SCHROYER, OF CHICAGO, ILLINOIS, ASSIGNOR TO THE ACME SUPPLY COMPANY, A CORPORATION OF ILLINOIS.

CAR-VESTIBULE DIAPHRAGM.

1,125,740.

Specification of Letters Patent.

Patented Jan. 19, 1915.

Application filed April 8, 1912. Serial No. 689,356.

To all whom it may concern:

Be it known that I, HARRY H. SCHROYER, a citizen of the United States, and a resident of the city of Chicago, in the county of Cook and State of Illinois, have invented certain new and useful Improvements in Car-Vestibule Diaphragms; and I do hereby declare that the following is a full, clear, and exact description of the same, reference being had to the accompanying drawings, and to the numbers of reference marked thereon, which form a part of this specification.

This invention relates to that class of diaphragms adapted for engagement between the diaphragm face plate and the vestibule face plate to afford a flexible connection therebetween. Heretofore such diaphragms have usually been constructed in accordion 20 folds, sometimes of strips of cotton (or other suitable) belting, which are riveted, sewed or stapled together edge to edge, with corresponding strips, so that each fold affords acute angles to receive dirt and moisture, and the inwardly directed folds of which, receiving and retaining the dirt and moisture, are soon rotted and injured, thereby necessitating repairs. It is also true that as heretofore constructed, sparks readily 25 find lodgment in such angles of the diaphragm, thereby frequently so injuring the diaphragm as to necessitate renewal.

The object of this invention is to afford a diaphragm so constructed as to be entirely 30 self-cleaning from dirt and sparks, and to afford a construction into which water or moisture cannot find access, thereby obviating the rotting of the fabric and consequent short life.

It is also an object of the invention to afford a construction wherein a desired 35 number of strips of fabric of suitable width are bent to afford U-shaped sections, and are engaged at their edges with the respective 40 face plates and the adjacent edges of another similarly shaped section, the smooth concave bend in the diaphragm section between the point of attachment therefor precluding the lodgment and retention of dirt 45 or sparks therein and insuring the quick 50 drainage of water or snow therefrom and the thorough drying of the fabric.

It is a further object of the invention to afford a construction permitting the actual 55 amount of material used in the diaphragm

to be reduced as compared with prior constructions, but in which great amplitude of movement of the diaphragm face plate relatively the vestibule face plate, is permitted without danger of straining or injuring the 60 diaphragm.

The invention embraces many novel features, and (in a preferred form) is illustrated in the drawings and hereinafter more fully described:

In the drawings: Figure 1 is a vertical section of a diagram embodying my invention. Fig. 2 is an enlarged fragmentary vertical section illustrating more particularly the construction of the top of the diaphragm. Fig. 3 is a section on line 3—3 of Fig. 2. Fig. 4 is an enlarged fragmentary section on line 4—4 of Fig. 2. Fig. 5 is an enlarged section on line 5—5 of Fig. 4.

As shown in the drawings: 1, indicates 75 the vestibule face plate, and 2, the diaphragm face plate, which are constructed as usual, and between which, and engaged to both, is the diaphragm embodying my invention. Said diaphragm comprises leg 80 sections 3, arch or shoulder sections 4 and 5, and top sections 6, and said sections are fastened together in any suitable manner to afford a tight joint at their ends. For this purpose, the ends of the sections may abut, and covering strips of thinner fabric may be secured thereover on each side thereof, or the same may be arranged together in overlapped relation at the ends, as shown in Fig. 2, with the end of each upper section 90 overlapping the end of the next lower to insure the free shedding of water and dirt therefrom, the overlapping end of the upper section being thus always directed downwardly on the outer side of the adjacent lower section. In constructing said sections, a strip of rubberized canvas or other suitable material such as cotton belting, and conveniently of approximately twelve inches in width, is bent longitudinally to afford a U-shaped cross section, as shown in Figs. 3 and 4, and engaged to a corresponding strip, the edges of which extend in the same plane therewith by means of staples 7, or by rivets, bolts, sewing or any suitable means to afford a permanent engagement or by detachable means affording a releasable engagement to rigidly bind said sections together. As shown, a channel strip 8, is engaged over the outwardly directed edges of 110

said diaphragm sections along the leg thereof, and the staples 7, are driven therethrough, as shown more plainly in Figs. 3 to 5 inclusive. The inner edge 10, of the 5 diaphragm section is then secured to the vestibule face plate by means of an apertured angle strip 11, and pins 12, set in said face plate to extend through said apertures and cotter pins 13, are engaged in apertures in the heads of said pins, as shown in Figs. 3 and 4, and as illustrated in one of my former patents, to-wit, No. 768,775, issued to me on the 20th day of August, 1904. The other edge of the diaphragm section, is engaged on bolts 14, which extend through the diaphragm face plate and through the edge of the diaphragm section and also through a retaining or clamping plate 15, and the nuts on said bolts act to firmly clamp said 20 plate against the diaphragm to hold the same in place.

In the construction illustrated in Figs. 2 and 3, the top of the diaphragm is made of double thickness the outer fold or layer B, 25 fitting closely in the U-shaped bend of the top reinforcing section 6, as shown in Fig. 3, with the edges thereof engaged together by similar means to those described whereby the diaphragm sections are engaged together, and to the respective face plates.

For this purpose, of course, stapling or other means of securing the edges together will suffice, and said edges may be covered by any suitable retaining means or may 35 themselves extend over and cover the edges of the diaphragm section 6. Said outer layer B, in the diaphragm top may be constructed of fire-proof and water-proof material and may be of a length to overlap and 40 extend beyond the joint between the section 5^a, of the diaphragm shoulder and the top section 6, and greatly stiffens the top.

As before stated, in the construction shown the outwardly directed central edges 45 of the diaphragm members are covered with a suitable angle strip or channel, which is secured to cover the same to prevent dirt or moisture finding its way therebetween and is engaged in place by means of staples 8, which extend therethrough and through the fabric. Such angle strips 8, for the top, articulate with, or are hinged to the corresponding angle strip 8, for the leg by bolts 8^a to permit a certain amount of relative 50 movement without danger of injury. Of course, it is not essential that metal be used for this purpose, or if a metal reinforcement be used, that it need be exterior to the edges of the diaphragm sections, as any of the well known means for covering such outwardly 55 directed edges, or for reinforcing the same, may be employed, if desired.

The operation is as follows: Obviously, diaphragms constructed as described afford 60 no entrant angles to receive dirt, dust and

moisture, as heretofore. Instead, each of the bent strips entering into the construction of the diaphragm, affords a gutter having a substantially cylindrically concave bottom. This is assured from the manner of attaching the parts together, inasmuch as the relatively wide strip of fabric, when bent to U-form, acts as a spring, and in consequence, the sides of the diaphragm lie flat against the face plate for a considerable portion of their width and extend inwardly from the channel 8, substantially in flat face contact against one another, thus affording a large curvature for the inner bend of the diaphragm. The top of the diaphragm being of double thickness, is greatly strengthened thereby and the tendency to sag is obviated as each layer of the fabric supports and braces the other to a considerable extent and serves to carry all stresses to the 35 diaphragm legs.

Owing to the construction described, a very large degree of expansion of the diaphragm is possible, so that although less material is actually employed than in diaphragms as heretofore constructed, the utmost limit of movement of the diaphragm face plate relatively the vestibule face plate is permitted without danger of injury to the diaphragm.

Very numerous details of construction and application may be varied. I have shown but a preferred form of the construction, and I therefore, of course, do not purpose limiting the patent to be granted on 100 this application, otherwise than necessitated by the prior art.

I claim as my invention:

1. A car vestibule diaphragm comprising a plurality of U-formed sections connected together, each section comprising a plurality of U-formed members, and metal guard binding strips for the edges thereof articulated together.

2. A car vestibule diaphragm comprising leg sections and top sections detachably secured together, said top members being of double thickness and metal guard binding strips on each of said sections and articulated at the connection of the leg and top sections.

3. In a car vestibule diaphragm, leg sections of single thickness and top sections each comprising a plurality of members of double thickness arranged in overlapped relation.

4. In a device of the class described the combination of leg sections of single thickness and top sections connected thereto of double thickness.

5. In a device of the class described top and leg sections and segmental sections connecting the same, said leg and segmental sections of single thickness and said top section of double thickness.

6. In a device of the class described a U-shaped top section of double thickness, U-shaped leg sections and U-shaped segmental sections connecting the top and leg sections, 5 and metal reinforcing binding strips secured over the edges of said sections and articulated at the point of connection of said leg and segmental sections.
7. In a device of the class described dia- 10 phragm sections of U-form, each section comprising top members of double thickness and leg members of single thickness and a binding strip secured on the edges of said sections.
- 15 8. In a car vestibule diaphragm of the ac- cordion type, a section comprising side and top strips, longitudinally folded to a U-cross-section, and shoulder pieces of a similar cross-section connecting the side and top 20 strips at the corners, substantially as described.
9. In a car vestibule diaphragm of the ac- cordion type, a section comprising side and top strips, longitudinally folded to a U- 25 cross-section, and a plurality of shoulder strips of a similar cross-section connecting the side and top strips at the corners.
10. A car vestibule diaphragm of the ac- cordion type, sections comprising side and 30 top strips and curved shoulder pieces all longitudinally folded to a U-cross-section, the shoulder pieces joining the top with the side strips with overlapping joints and the bottom of the shoulder pieces extending 35 in a substantially curved line between the point of junction with the top and side strips.
11. A car vestibule diaphragm of the ac- cordion type, each section comprising side 40 and top strips and shoulder pieces all longitudinally folded to a U-cross-section, the shoulder pieces joining the top with the side strips with intermediate overlapping joints, and the bottom of the shoulder pieces 45 extending in a substantially curved line between the point of junction with the top and side strips.
12. A car vestibule diaphragm of the ac- cordion type, each section comprising side
- and top strips, and curved shoulder pieces 50 all longitudinally folded to a U-cross-section, the shoulder pieces joining the top with the side strips with intermediate overlapping joints, and the bottom of the shoulder pieces extending in a curved line be- 55 tween the point of junction with the top and side strips.
13. A car vestibule diaphragm of the ac- cordion type, each section comprising two side strips and a top strip, and curved shoul- 60 der pieces all longitudinally folded to a U-cross-section, the shoulder pieces joining the top with the side strips with intermediate overlapping joints.
14. A car vestibule diaphragm of the ac- cordion type, each section comprising two side strips and a top strip of double thick- 65 ness, and shoulder pieces all longitudinally folded to a U-cross-section, the shoulder pieces joining the top with the side strips 70 and the bottom of the shoulder pieces ex- tending in a curved line between the point of junction with the top and side strips.
15. A car vestibule diaphragm of the ac- cordion type, each section comprising side 75 and top strips, and a plurality of shoulder pieces secured thereto in overlapped relation and all longitudinally folded to a U- cross-section.
16. A car vestibule diaphragm of the ac- 80 cordion type, each section comprising two side strips a top strip of double thickness, and shoulder pieces of single thickness all longitudinally folded, the shoulder pieces joining the top with the side strips. 85
17. A car vestibule diaphragm of the ac- cordion type, each section comprising two side strips, a top strip of double thickness, and corner pieces of single thickness join- 90 ing said top with the side strips.
- In testimony whereof I have hereunto subscribed my name in the presence of two subscribing witnesses.
